WARP FABRIC

Paul Schönfeld, Chemnitz, Germany

Application December 16, 1937, Serial No. 180,096
In Germany October 23, 1937

3 Claims. (Cl. 66—195)

This invention relates to a two-machine plain knitted warp fabric provided with rubber warp threads.

It has been proposed already to produce two-machine plain knitted warp goods provided between the two thread groups with rubber warp threads in such manner that the rubber threads do not run back from the transverse cut edges of the fabric, since warp goods are chiefly used as cutting material from which portions are cut off and sewn together to form wearing apparel, etc. This end is attained by recurrently tying up the rubber warp threads in the goods so as to form meshes and omitting lateral racking of the threads of the upper thread group in the courses where these meshes are formed. This is done to prevent the meshes formed by the rubber threads from sticking out of the fabric and thereby rendering the goods unsightly. In the next course 20 the upper thread group carries out underlaying operations.

From these known fabrics the warp goods according to the present invention differ in so far as the threads of the upper group also form a mesh in the course following the courses in which the rubber warp threads form meshes, so that the heads of the meshes formed by the rubber threads are caught by the feet of these meshes of the upper group.

30 In this way, the upper thread group renders the additional service of catching the meshes of the rubber warp threads which are thus fixed at the mesh-forming points in an absolutely reliable manner.

35 By way of example, one form of the invention is illustrated in the drawing which shows a lapping diagram to bring out clearly the composition of the fabric.

The warp fabric consists of the two thread groups 1 and 8, the group 1 being the upper one and forming an ordinary ground fabric, such as a plain tricot. The thread group 8 is the upper one and worked with overlaying and underlaying operations. For the sake of clearness, only one 40 thread is shown of the group 8 which chiefly serves for forming ribs in the ground fabric built up by the thread group 1, as described in Patent No. 2,012,355. For this purpose, the threads of the group 8 are alternately racked once in the 45 same direction as the threads of the group 1 and then again in opposite direction thereto. In the courses 1 to 3 where the upper thread group 8 carries out underlaying operations racking is effected in the same direction as racking of the 50 lower thread groups 1. In the courses 4, 5 rack-

ing is performed in opposite direction, and in the course 6 lateral racking of the upper thread group 8 is omitted. The mode of racking of the upper thread group 8 is thus repeated every six courses. Between the two thread groups 1, 8 the rubber warp threads 9 are worked in of which only one is shown. The rubber warp threads are recurrently tied up in the fabric by forming meshes therein, which is effected simply by placing the threads around their needles at the points concerned. 5 According to the invention, the threads of the upper group 8 also form a mesh in the course following the courses in which the rubber threads 9 form one. For example, when the rubber threads 9 form a mesh in the courses 3, as shown, the upper thread group 8 will form meshes in every course 4. The result is that the heads of the meshes formed by the rubber threads 9 are caught by the feet of these meshes of the upper thread group 8 and each rubber thread is thus reliably 10 secured against running back.

In the known fabrics mentioned lateral racking of the lower thread group 8 is omitted in the courses in which the rubber warp threads 9 form meshes to prevent the rubber-thread meshes from 15 being raised out of the fabric. The same effect is attained by underlaying of the upper group 8 in the courses concerned, i. e. in the courses 3, as shown.

If the rubber warp threads 9 are gathered in 20 a single lapping machine in the usual manner, all threads 9 will be tied up by forming meshes in one 25 and the same course. To avoid this it is possible to subdivide the threads 9 into two or more groups and to guide these groups independently of one 30 another in a corresponding number of lapping machines. It thus becomes possible to tie up the threads 9 of one group in mesh-forming manner 35 in the other group or groups, so that the meshes formed by these threads will be staggered relative 40 to one another in the fabric. The rubber threads 9 of one group may further be placed to the left 45 about the needles and those of the other group to the right, whereby the lateral action of the rubber threads upon the fabric is compensated.

During production of the fabric according to the invention the thread group 8 is therefore gathered in the upper lapping machine and the thread group 1 in the lower one whilst the rubber warp threads 9 are guided in a lapping machine 50 disposed between these two machines.

I claim:—

1. Two-machine plain knitted warp fabric which comprises two thread groups with rubber warp threads inserted between them and recur- 55

rently tied up in a mesh forming manner and in which the threads of the upper group also form a mesh in the course following the courses in which the rubber warp threads form meshes, the heads of the meshes formed by the rubber threads being caught and held by the feet of said meshes formed by the threads of the upper thread group.

2. Warp fabric according to claim 1, wherein

the upper thread group is underlaid in the courses in which the rubber warp threads form meshes.

3. Warp fabric according to claim 1, wherein the rubber warp threads comprise a plurality of groups tied up in mesh-forming manner at points staggered relative to one another in the longitudinal direction of the fabric.

PAUL SCHÖNFIELD.
